J. PURETZ & B. COHEN.
SAD IRON.
APPLICATION FILED NOV. 10, 1917.

1,275,743.

Patented Aug. 13, 1918.

UNITED STATES PATENT OFFICE.

JULIUS PURETZ, OF BROOKLYN, AND BARNEY COHEN, OF NEW YORK, N. Y.

SAD-IRON.

1,275,743.

Specification of Letters Patent. Patented Aug. 13, 1918.

Application filed November 10, 1917. Serial No. 201,320.

To all whom it may concern:

Be it known that we, JULIUS PURETZ, a citizen of the United States, and a resident of the city of New York, borough of Brooklyn, in the county of Kings and State of New York, and BARNEY COHEN, a citizen of the United States, and a resident of the city of New York, borough of Bronx, in the county of Bronx and State of New York, have invented a new and Improved Sad-Iron, of which the following is a full, clear, and exact description.

An object of the invention is to provide a simple, efficient and inexpensive sad iron within which the flame is generated by a gas burner. It is an improvement over our Patent No. 1,150,703 issued August 18, 1915, from which it is characterized by the provision of a detachable ironing or bottom plate.

Another object of the invention is to provide a sad iron having a detachable ironing plate provided with means entering the hollow of the iron and subject to the direct attack of the flames of the burner.

Another object of the invention is to provide an ironing plate which permits a free access of air through the bottom of the hollow of the iron so as to facilitate combustion within the iron and thereby increase the efficiency of the burner.

With the above and other objects in view, the nature of which will more fully appear as the description proceeds, the invention 35 consists in the novel construction, combination and arrangement of parts as herein fully described, illustrated and claimed.

In the accompanying drawings, forming part of the application, similar characters of 40 reference indicate corresponding parts in all the views.

Figure 1 is a side elevation of our iron partly in section on line 1—1, Fig. 2;

Fig. 2 is a horizontal section on line 2—2, 45 Fig. 1;

Fig. 3 is a transverse section on line 3—3, Fig. 1; and

Fig. 4 is a perspective view of the detachable ironing or bottom plate.

Referring to the drawings, 5 is the hollow casing the bottom 6 of which is provided with interior transverse corrugations against which the flame of a burner 7 is adapted to play. The bottom has also a longitudinal 55 central slot 8 through which air is to be sup-

plied to facilitate the combustion of the gases within the hollow casing 5.

The bottom 6 has also apertures 9 to each side of the slot into which lugs 10 of a detachable bottom plate 11 are adapted to enter. These lugs 10 are corrugated to match the corrugations of the bottom 6, and against which corrugated lugs the flame of the burner is adapted to play and thereby convey the heat directly. The plate 11 has a central groove 12 which is adapted to align with the slot 8. It has also transverse grooves 13 leading from the groove 12 to the margin of the plate. These grooves 13 convey the air to the groove 12 from where it enters the slot 8.

Flat surfaces or shoulders 14 of the plate are adapted to contact with the bottom of the hollow casing 5, and thereby the ironing plate 11, in addition to being heated directly 75 through the lugs 10, is also heated by contact with the bottom of the casing. The lugs 10 prevent any lateral or longitudinal movement of the plate relative to the casing. To retain the casing against the bottom, screws 80 15 are employed, for which threaded openings 16 are provided in the ironing plate.

The provision of the contacting shoulders 14 gives ample contacting surface between the bottom and the detachable plate and also 85 assures a perfect bearing for the hollow of the casing, with ample opening in the detachable plate for the admission of air to the interior of the casing. The detachable plate 11 has also end openings or grooves 17 which 90 lead to the groove 12 so as to increase the air supply thereto.

We claim:

1. A sad iron having a hollow casing the bottom of which has a longitudinal central 95 slot and apertures to each side of said slot, a bottom plate securable to the bottom of the hollow casing having lugs adapted to enter into the apertures in the bottom, and a burner in the hollow of the casing adapted 100 to play its flames on the bottom of the hollow and the lugs of the bottom plate; said bottom plate having grooves from the margin for admitting air to the central slot of the bottom of the hollow casing.

2. A sad iron having a hollow casing provided with a central longitudinal slot and apertures to each side of the slot, a detachable plate having lugs adapted to enter the apertures in the bottom whereby longitudi- 110

nal and lateral movement of said plate relative to the bottom of the hollow casing is prevented, means for securing the bottom plate to the bottom of the hollow casing whereby the same is retained against the bottom of the hollow casing, and a burner within the hollow casing for playing its flame on the bottom of the hollow casing and upon the lugs of the plate engaging the apertures in the bottom of the hollow casing, said plate having a central longitudinal groove adapted to register with the slot in the bottom of the hollow casing, said plate having also transverse grooves leading from the margin to the longitudinal groove, whereby air is supplied to the slot in the bottom of the hollow casing.

3. A sad iron comprising a hollow casing having an internally corrugated bottom, said bottom having a longitudinal slot and apertures to each side of the longitudinal slot, a bottom plate adapted to contact with the bottom of the hollow casing, lugs on said plate adapted to project into the hollow of the casing through the apertures in the bottom of the hollow casing, said lugs having a corrugated top, and a burner in said hol-

low casing adapted to play its flames on the corrugations on the bottom and the corrugations of the lugs, said bottom plate having longitudinal and transverse grooves for supplying air to the central slot of the bottom of the hollow casing.

4. A sad iron comprising a hollow casing the bottom of which has apertures, a bottom plate detachably connected to the bottom of the hollow casing and having projections entering through the apertures into the hollow casing, and a burner in the hollow casing adapted to play its flames upon said projections of the bottom plate so as to heat it directly, said projections presenting a corrugated surface within the casing to increase the surface upon which the flames of the burner are playing.

5. In a sad iron having a hollow casing and a burner in the casing, a detachable bottom plate having projections entering the hollow casing, said projections presenting a corrugated surface within the casing to expose a larger surface to the flames of the burner.

JULIUS PURETZ.
BARNEY COHEN.
